BY Ernest E. Wood

ATTORNEY.

UNITED STATES PATENT OFFICE

SAMUEL J. MANSFIELD, OF DALLAS, TEXAS

PISTON

Application filed December 13, 1928. Serial No. 325,819.

This invention relates to pistons for internal combustion engines and it has particular reference to that type of piston having a head and a guide composed of metals having 5 different characteristics, each performing its peculiar function in bringing about uniformity of operation and the principal object of the invention resides in the improved manufacture of a piston, possessing the prerequisite of expansion and contraction in accordance with the changes of motor temperature, yet having the characteristics of a single piece piston.

Another and important object of the invention resides in the provision of an improved lubricating system by which the piston may be properly lubricated in operation, and by reason of which the annoyance of "pumping" oil, so common to the ordinary 20 piston will be eliminated.

Another object of the invention resides in the peculiar construction of the improved piston, through the medium of which, not only are the foregoing and other objects attained, 25 but also teaching the economical construction of a piston comprised of different metals having a co-efficient of expansion combined with its lubricating system, which metes out the proper amount of lubricating medium, 30 yet providing for instantaneous lubrication for the walls of the cylinder after they have been drained over a period in which the pistons have been motionless therein.

With the foregoing objects as paramount, 35 the invention resides further in the salient features of construction and arrangement of parts, hereinafter more specifically described and shown in the accompanying drawings, wherein;

40 Figure 1 represents a side elevational view of a piston constructed according to the present invention.

Figure 2 is an axial sectional view thereof.

Figure 3 is a sectional view on lines 3—3 of Figure 1, and

Figure 4 is a detail view in perspective of one of the sections forming the guide for the piston head.

Continuing now more in detail with the drawings, it may be first stated for the sake

of differentiation that a piston in the nature of a single piece piston, yet having the ability to resist the effects of expansion and contraction due to sudden temperature changes, has been long sought for. And in 55 this connection it may be mentioned that such a piston must be composed of metals having a decidedly different reaction to heat and cold. The problem has been to combine these metals in such manner that the effect 60 of expansion and contraction of one element under severe temperature changes would not be such as to cause injury to the other. Moreover, it is desirable that the metal of which the 65 guide or skirt of the piston is comprised be of slow wearing qualities, yet being capable of adjusting itself to the walls of the cylinder, which have become worn to such an extent as to be untrue and to the expansion and contraction of the head, which is the part of the 70 piston undergoing the most severe strain.

In so adjusting itself to the walls of the cylinder, the objectionable "slapping" which occurs when the cylinder becomes out-of-round through the use of the ordinary piston, 75 is eliminated. The present invention advances three distinctive improvements therefore, namely, combining two metals in the construction of a piston capable of co-operative reaction to sudden temperature changes 80 without ill effect; a thorough lubricating system by which this medium is held in check to prevent overlubrication, and a means by which the piston guide may adjust itself to the cylinder walls to prevent piston "slapping" 85 and undue wear.

Accordingly, 1 designates generally the head in which ring grooves 2 are provided as in the conventional pistons. This head is of cast metal, preferably cast iron, aluminum, or the like and, as will become manifest later, may be either cast into the guide, to be presently described, or cast separately and welded to the guide.

The guide, which is comprised of two semi-circular members 3, one of which is illustrated in Figure 4, is affixed to the head in the manner shown and to be later described more in detail, and has an annular depression 4 about its center, which serves in the capac- 100

ity of an oil reservoir, containing sufficient oil under operating conditions to effectively lubricate the cylinder walls.

It will be particularly noted that the members 2 are of corresponding size and shape, that is to say, are of such similarity that a single die may be used in making both, which is an important feature in economical manufacture of the piston.

When fitted together in the manner exemplified in Figure 1, an oblique slit 5 is left on either side of the guide, both above and below the opening 6. A limited, but sufficient amount of expansion and contraction of the ends of the guide is allowed by reason of these slits, therefore, since the portions of the guide opposing the annular depression are the only parts of the piston coming into direct contact with the walls of the cylinder, the expansion and contraction permitted by the slits 5 is sufficient to enable the piston to, at all times, adjust itself to the walls of the cylinder, without default in the efficient performance of the piston. Moreover, due to the oblique disposition of the slits 5, scoring of the walls of the cylinder by exposed, irregular edges is obviated.

With further reference to the opening 6, into which the slits 5 extend, it will be noted that half of this opening is cut from one of the sections 3 while the other half is cut from the companion section. The purpose in making this opening of oblong shape is to provide for ready vertical alignment of the wrist pin bearings 7 cast integral with the head, without requiring too exacting effort when assembling the piston.

It is intended for the sake of strength and durability, that the elements be welded together to complete the piston, and in this connection reference is made to Figure 3. The head 1 is first poured into a mould in which a pattern has been embedded to provide for a series of annularly spaced indentations 7a around the lower edge 8, corresponding with the inwardly extending punched projections 9 about the waist of the guide members 3. It is obvious that when the head and the two guide sections are joined together in the relationship shown in Figures 1 and 2, these projections will enter the indentations 7a and upon filling the indentations with molten metal under an electric or other welding torch the elements are held in positively fixed relationship having the characteristics of a single piece piston. After having so joined the head and guide sections together, the piston is placed upon a lathe and turned to proper standard size.

It is obvious also that the head and guide sections may be as readily assembled by arranging the guide sections 3 in a form in which an impression of the head 1 has been made in the sand by a matrix, and pouring the molten metal through a hole in the top

of the form. The metal of course, when chilled, will attain the form of the head shown, and the apertures 10 will have been filled by the metal, the latter flowing around the projections 9 which, after having been embedded in the metal forming the head, provide a positively secure locking means. The composite piston thus formed is then placed in a lathe as in the previous case and finished to the desired size.

In producing a composite piston as last described, that is, in casting the head integral with the guide, there is a likelihood that the metal forming the head will chill before fusing with the metal guide sections and in the absence of means to offset later effects of this condition, the guide sections might give trouble in working loose. In the present invention, the projections 9 extending inwardly of the walls of the guide sections 3 form a most effective anchor in the manufacture of pistons in this manner to provide the maximum of efficiency in the operation of this particular type of composite piston.

It is more desirable, however that the head and guide sections be welded together in the manner first described, the method of construction embodying substantially the same principle as in the other case.

Referring now particularly to the oiling system of the improved piston, Figure 2 shows by following the arrows, the course taken by the lubricant during the reciprocative movements of the piston. It is understood that a positive seal is provided in the cylinder by the piston, as hereinbefore stated, and known to those familiar with the art as being the desideratum of efficiency, yet the openings 11, and 12, allow passage of the minimum amount of oil to properly lubricate the piston without flooding the rings, which is the annoying disadvantage found to exist in a great number of pistons seeking to provide the desirable feature of flexibility under all operating conditions.

It will be observed that the openings 11 and 12 are of slightly different nature, the former being only a plain hole while the latter provides an overhanging lip 13. The object of this lip is to deflect oil which has been splashed upward into the piston by the crank shaft, and descends along the inner walls of the piston.

As the piston approaches the lower extremity of the cylinder, the lower edge thereof receives a bath of oil and at the same time, the oil is splashed upward into the head. The oil is carried upward by the piston as it moves toward the top of the cylinder, as shown by the arrows, exteriorly of the walls of the guide in Figure 2 and in moving upward, the film of oil remaining on the walls of the cylinder in the preceding stroke is wiped off by the deflected portion

of the guide at *a*, and takes the course shown by the arrow at this point, into the area between the walls of the head 1 and guide, indicated at *b*, whereupon it drains out of this area, through openings 11 spaced annularly about the guide, into what is, under operating conditions, a reservoir 4, hereinbefore mentioned. The excess oil in this reservoir finds an escape through opening 12 at the bottom of the reservoir 4, back into the inner surface of the guide, whereupon it continues as indicated by the arrows, downward into the crank case.

It is a desirable feature in a piston to provide for immediate lubrication for the piston upon its first stroke after a period of idleness, that is, after the film of oil has had sufficient time to drain back into the crank case, leaving the cylinder walls comparatively dry. This feature is provided in the present case by leaving an annular space at *c* below the openings 11, and above the point of connection between the head and guide. Sufficient amount of oil is left remaining in this reserve to provide a cushion of oil upon which the piston may ride in its initial movement, or until it receives a supply from the crank case.

It is apparent from the foregoing that at no time is it possible for an over supply of oil to pass above the guide to be handled by the oil ring. Under ordinary conditions, this ring, or the ring within the lower groove 2, is required to restrain the oil from passing above the piston and if this ring is not entirely effective, at all times, the piston will act to literally pump the oil into the firing area of the cylinder, whereas, in the present case, only a thin film is permitted to interpose the piston and cylinder wall, and at no time does it attain such volume as to "drown out" the oil ring of the piston even under the most strenuous operating conditions. The reservoir provided in the annular depression 4 is at all times kept replenished by the passage of oil in the manner described whether the motor is operating at a high rate of speed or idling.

It is obvious from the foregoing that the present invention, while being composed of metals having a different reaction to strain or heat, its construction is such as to provide for stress and changes in temperature, without affecting its performance in the cylinder.

Manifestly, the construction shown is capable of considerable modification, or such modification as is considered within the scope of the appended claims is considered within the spirit of the invention.

I claim—

1. In a piston, a head, a guide secured to the head, there being an annular space between the upper end of the guide and the head which opens outwardly, said guide having openings which communicate with the

lower part of said space and having an annular space on its exterior adjacent to said openings and further having other openings at the lower part of the external annular space, and fixed lips overhanging the said other openings and formed to deflect oil splashed into the piston along the interior thereof.

2. A piston having a head and a guide composed of independent sections cast integral with the head, said guide having anchoring elements between its top and bottom which are embedded in the head, the adjacent end edges of the sections being free of the head and spaced throughout their lengths to allow for expansion and contraction.

3. A piston having a head and a sectional guide cast integral with the head, said guide having anchoring elements between its top and bottom which are embedded in the head, the adjacent end edges of the sections being inclined and free of the head and spaced and further having cut-outs which conjointly define an opening disposed between the top and bottom of the guide.

4. A piston having a head and a sectional guide cast integral with the head, said guide having integral anchoring means struck-out therefrom and which are cast into the head, the confronting edges of the sections being spaced and free of connection with the head.

In testimony whereof I affix my signature.
SAMUEL J. MANSFIELD.
